ERNESTO MENDOZA AND RAMÓN SALA, OF MEXICO, MEXICO

TAKE UP DEVICE FOR LOOMS

Application filed February 13, 1931. Serial No. 515,609.

This invention relates to improvements in looms and has particular relation to means for taking up the cloth during the operation of weaving.

5 Another object of the invention is the provision of means of the above character which may be accurately adjusted in accordance with the number of picks of the loom, so that imperfect places in the weave

10 will be avoided.

With the above and other objects in view, the invention further includes the following novel features and details of construction, to be hereinafter more fully described, illus-

15 trated in the accompanying drawings and pointed out in the appended claim.

In the drawings:—

Figure 1 is a view partly in end elevation and partly in section illustrating the invention.

20 Figure 2 is a sectional view on the line 2—2 of Figure 1.

Referring to the drawings in detail wherein like characters of reference denote corre- 25 sponding parts, the reference character 8 indicates the winding roll of the loom, while the reference character 1 indicates the driv-

ing shaft.

Keyed upon the winding roll 8 is a sleeve 30 17. The inner end of this sleeve rests against a shoulder provided at the end of the wind- ing roll and is provided at this point with a beveled flange 7. Mounted upon this sleeve 17 is a collar 15 which forms one member of

35 a clutch mechanism to be later described. This collar is provided with a recess to receive the flange 7 and is forced upon said flange and locked to the sleeve through the medium of a nut 9 which is provided with an

40 operating arm or handle 10. The sleeve 17 is held against axial movement by means of a nut 19 which is threaded upon the end of the winding roll 8 and which is provided with a crank handle 20.

45 The collar 15 is provided with a plurality of spaced recesses 18 in its periphery, the said recesses having inclined bottom walls. These recesses are closed by means of rings 3 and 14, the said rings forming the outer walls of

50 for the accommodation of rollers 5. Two rollers are provided in each of the pockets and are arranged end to end, so that one roller will engage the inner periphery of the ring 3 and the other roller the inner periphery of the ring 14. These rollers are held in place by means of rings 6 which threadedly engage the collar 15 and which are provided with sockets 11 for the reception of a suitable tool.

55 Extending from the ring 14 is an arm 14', see Figures 1 and 2, and this arm is adapted to be suitably fixed to the stretching table or other convenient part of the loom (not shown).

60 Extending radially from the ring 3 is a threaded arm 13 and threadedly mounted upon this arm is an interiorly and exteriorly threaded sleeve 2. Threadedly engaged upon the sleeve 2 is a clip 12 and pivotally mounted between the ends of this clip as 65 shown at 12' is one end of a rod or arm 21. The other end of this arm is threadedly engaged with an eccentric strap 22 which surrounds an eccentric mounted upon the drive shaft 1 and which causes the rod 21 to re- 70 ciprocate as the shaft 1 rotates.

75 It will be seen from the foregoing description and accompanying drawings that opera- 80 tion of the shaft 1 will impart an oscillatory movement to the ring 3, the degree of which is governed by the position of the clip 12 upon the sleeve 2, the position being regu- 85 lated by the number of picks of the cloth. Movement of the ring 3 in a clockwise direc- 90 tion will lock this ring to the collar 15 and will thus impart a like movement to the col- 95 lar, and as this collar is locked to the winding roll 8, the latter will be likewise moved. Movement in a reverse or anti-clockwise direc- 100 tion will permit the ring 3 to run free, so that no movement of the collar 15 will occur. The ring 14 will hold the roll 8 against retro- grade movement.

105 Each of the recesses or pockets 18 is pro- 95 vided at one end with a cushioning plunger 4 against which the rolls 5 engage when the ring 3 is moving in an anti-clockwise direc- 100 tion. This permits free rotation of the collar and takes up lost motion when the ring be-

gins its movement in an anti-clockwise direction.

The sleeve 2 and arm 13 are provided with transverse openings for the reception of a sealing wire 24 so as to prevent tampering with the adjustment of the device. The outer end of the sleeve 2 is provided with a cap or collar 23 which is secured to the arm 13 by means of a screw.

10 The invention is susceptible of various changes in its form, proportions and minor details of construction and the right is herein reserved to make such changes as properly fall within the scope of the appended claim.

15 Having described the invention what is claimed is:—

20 In a take up mechanism for looms, a clutch mounted upon the winding roll of the loom to impart a step by step rotation thereto and including a ring member having a radially disposed arm, a sleeve journaled upon said arm and having an external thread means for fixing the sleeve with relation to the arm, a clip 25 threaded upon the sleeve and a rod pivotally connected with the clip and adapted to be operatively connected with the shaft of the loom.

25 In testimony whereof we affix our signatures.

30 RAMÓN SALA.
ERNESTO MENDOZA.
